UNITED STATES PATENT OFFICE.

LOUIS F. LINDSTROM, OF BRIDGEPORT, CONNECTICUT, ASSIGNEE TO HARVEY HUBBELL INC., OF BRIDGEPORT, CONNECTICUT, A CORPORATION OF CONNECTICUT.

ELECTRIC-LAMP PUSH-SOCKET.

1,098,741.

Specification of Letters Patent. Patented June 2, 1914.

Application filed August 2, 1912. Serial No. 712,868.

To all whom it may concern:

Be it known that I, LOUIS F. LINDSTROM, a subject of the King of Sweden, and resident of Bridgeport, in the county of Fairfield and State of Connecticut, have invented 5 certain new and useful Improvements in Electric-Lamp Push-Sockets, of which the following is a specification.

This invention relates to new and useful 10 improvements in incandescent lamp sockets, and refers particularly to push button operating mechanism for use in connection with sockets of the type shown and described in patent to Hubbell #565,541.

15 The object of the invention is to improve upon incandescent lamp sockets of this general type by providing a single push button operating mechanism, that is at all times in position to be operated and which by successive operations serves to alternately turn 20 the current on and off. The advantages of an operating mechanism of this sort is that the socket may be operated by one hand, in a way that the fingers of the hand will 25 steady the light, while the thumb of the same hand presses the button without materially disturbing the position of the light as would be the case with many other forms 30 of sockets, including the pull sockets which invariably cause the lamp to swing for a time after being operated by the chain; further to provide a simple, compact and 35 practical form of socket which may be manufactured and sold at practically the same price as the pull socket.

With these and other objects in view the invention resides and consists in the novel construction, combination and arrangement 40 of parts shown in the accompanying drawings forming a part of this specification, and upon which,

Figure 1, is a side view of my improved electric lamp socket, the shell or casing thereof being shown in section. Fig. 2, is a 45 sectional plan view taken on line 2-2 of Fig. 1, the casing being omitted. Fig. 3, is a vertical sectional view taken on line 3-3 of Fig. 2 showing the two insulating blocks and parts connected therewith. Fig. 4, is a 50 sectional plan view taken on the same line as Fig. 2, but illustrating the push button and connected parts in an operated and different position from Fig. 2. Fig. 5, is a side elevation of the socket mechanism 55 shown in the preceding figures and also in

an operated position to agree with the position of the parts shown in Fig. 4, and, Fig. 6, is a detached plan view of the rotatable metal plate which is operated from time to time to make and break the connections of the socket.

Referring in detail to the characters of reference marked upon the drawings 10 denotes a shell or casing for inclosing the operative parts of the socket, 11 an insulating lining therefor and 12 a cap for the shell which is also provided with an insulating lining 13. This shell obviously serves to inclose the operative parts of the socket which are contained within a frame formed 60 in part of insulating blocks, posts, etc., as will later be explained, the said parts being detachably contained within the shell and cap.

14 represents the upper insulating block 75 and 15 the lower insulating block.

16, 17 and 18 represent metal posts, the upper and lower ends of which are attached to the respective insulating blocks by means of screws as shown. The said posts 16 and 80 17 are provided with binding screws 19 and 20 for the attachment of the two electric wires 21 that are disposed up through pockets 22 of the upper block 14 and carried out through the central opening 23 in 85 the hub of the cap 12.

An additional support 24 is arranged along side of the post 18 and is also secured to the two insulating blocks 14 and 15 in a way to be held in a fixed position. A tubular guide 25 is suitably secured in this latter post 24 to accommodate the push button 26 that is slidably mounted therein. One end of a link 27 is pivotally connected to this push button 26 and the other end is pivoted 95 to a stud secured to an operating member 36 mounted on a post 29.

A rotary contact plate 28 is mounted upon the central post 29 that is insulatedly supported between the two insulating blocks 100 14 and 15. This plate is provided with two angularly deflected yielding arms 30 that are formed from the metal of the plate and are adapted to engage the inclined raised surfaces 31, 32 and 33 on the lower 105 insulating block 15. The plate 28 is further provided with shoulders 34 that are preferably formed when stamping out the plate, as shown in Fig. 6, leaving the plate and its shoulders free to be engaged by the 110

several beveled teeth 35 on the under side of the operating member 36. This operating member is pivotally hung upon the before mentioned post 29 in a way to be operated by the push button and in turn rotate the contact plate. One end of a spring 37 is connected to the upper insulating block 14 and its other end is attached to the said operating member 36 in a way to hold the 5 said operating member in its normal position, as shown in Figs. 1, 2 and 3. The teeth of the said operating member are at all times in engagement with the plate and serve to engage the shoulders of the contact plate so that when the push button 26 is pressed in, the operating member will 10 rotate the said contact plate 28, causing its downwardly extended yielding arms 30 to be drawn around upon the inclined surfaces 31, 32 and 33 of the lower insulating block 15 and so that the two said arms will 15 simultaneously engage the respective inclines of the base and the inclined fixed plates. There are obviously four of these 20 raised incline surfaces formed on the lower insulating block 15, two oppositely located ones of which are bare and the other two are covered with metal. The metal covering 25 or plate 32 is secured in position by a screw 38 that also electrically connects it with the said post 16 and binding screw 19. The other metal plate 33 connects with the central screw 39 and clip 40 for connection with the lamp when the same is screwed 30 in position in the threaded shell 41 of the socket and made in to register with the clip. This operating member 36 is provided with an extended arm 42 to engage the post 16 and to form a stop to limit the 35 action of the before mentioned spring 37 connected to said operating member. The spring 37 also exerts a downward pressure upon both the rotary plate 28 and the operating member 36 so as to insure the arms 40 of the said plate snugly contacting with the metal covered inclined plates 32 and 33 secured to the lower block. This rotary contact plate can obviously be moved in but one direction by reason of the shoulders formed against the high ends of the 45 inclined surfaces 31, 32 and 33 and by reason of the teeth 35 of the operating member 50

being beveled to ride back over the surface of the rotary plate.

From the foregoing construction it will 55 be noted that with an inward thrust or push of the button 26 as shown in Figs. 1 and 2, the operating member is swung around against the action of its spring, to the position shown in Fig. 4, and therewith 60 rotates the operating plate a quarter turn, drawing its oppositely arranged yielding arms from the inclined insulated surfaces and upon the inclined metal surfaces 32 and 33. A second operation will further 65 draw the arms from the said inclined metal surface back upon the insulated surfaces, thereby making and breaking the circuit through the socket with each push of the button. The spring 37 further serves to 70 force the button out again when released, to return the parts to their normal position. When the rotary plate of the socket is positioned so that the yielding arms are in contact with the contact plates 32 and 33, 75 the current will obviously pass through the rotary plate to complete the circuit, whereas when given a quarter turn the contact again becomes broken.

Having thus described my invention what 80 I claim and desire to secure by Letters Patent is:—

In an electric switch socket, the combination with a shell, of two insulating blocks 85 spaced apart by a plurality of posts adjacent their outer edges, a central post connecting said blocks, an operating plate, a contact plate, a spiral spring circumscribing said central post with its upper end attached to the upper of said insulating 90 blocks and its lower end attached to the upper face of said operating plate and an outwardly extending arm carried by said operating plate adapted to engage with one of said posts to limit the return movement of said operating plate. 95

Signed at Bridgeport, in the county of Fairfield and State of Connecticut, this 24th day of July, A. D., 1912.

LOUIS F. LINDSTROM.
